INVENTOR
JOHN G. ANDERSON

BY
J. L. Rivers.

ATTORNEY

UNITED STATES PATENT OFFICE.

JOHN G. ANDERSON, OF PYSH, WASHINGTON.

ROPE-GRIP.

1,367,762.

Specification of Letters Patent.

Patented Feb. 8, 1921.

Application filed October 2, 1920. Serial No. 414,303.

To all whom it may concern:

Be it known that I, JOHN G. ANDERSON, a citizen of the United States, residing at Pysh, in the county of Clallam and State 5 of Washington, have invented a new and useful Rope-Grip, of which the following is a specification.

My invention relates to improvements in devices for holding ropes in fixed positions, 10 especially wire ropes; and the objects of my improvement are to provide a rope fastener particularly suitable for use in logging operations, wherein a high lead for donkey engines is established on a tree, a pole or the 15 like, by means of blocks and tackle, and guy ropes, for the purpose of steadyng the apparatus are extended therefrom. The chief function of this fastener is to hold said guy ropes in operative position.

20 I attain these objects by the mechanism illustrated in the accompanying drawing, in which—

Figure 1 is a view of the device in elevation and partly in plan, showing sections of 25 rope in gripping engagement therewith; Fig. 2 illustrates the inner portion of one of a pair of movable clamping shoes with which the device is provided, having recesses 30 conforming substantially to the strands of a rope; Fig. 3 is a longitudinal sectional view, partly cut away, of a portion of the fastener, showing the rope seated between a clamping shoe and one of the rope casings, the eccentric links being released from engagement 35 with the shoe; Fig. 4 is an elevation of one of said shoes, showing its inner surface provided with recesses designed to conform to the strands of a rope; Fig. 5 is a cross-section drawn on the line 5—5, of Fig. 1; Fig. 40 6 is a cross-section of a modified form of the device, wherein said shoes are dispensed with, and in lieu thereof the links are provided with concave end faces adapted to grip a rope.

45 The device comprises a pair of casings 1, substantially U shaped in cross-section and adapted to receive and hold sections of rope, 2. The inner curved surfaces of these casings carry a number of recesses, 3 in Fig. 3, 50 practically conforming to the strands of a rope, to afford a better grip or clutch on said rope. These complementary casings, necessarily of rigid construction, are connected by a plurality of links 4. The drawings indicate but three links, but any number 55 can be utilized to meet the size and re-

quirements of the device. The ends of each link, while defining in outline the segment of a circle, are, in the preferred form of construction, right angular in relation to the 60 body of the link. These links are pivotally and eccentrically mounted as shown at 5 between lugs 6 which extend in pairs from the casings 1, the ends of the links presenting cam faces. Loosely mounted within each cas- 65 ing is a clamping shoe 7, which is retained in the casing by its ends projecting over the edges thereof, as indicated at 8. The inner curved surface of each shoe is provided, as shown at 9, with a plurality of recesses 70 adapted to conform to the strands of a rope and are complementary to the recesses in the curved portions of the casings. The outer surface of each shoe is operatively associated with the cam faces of the links, as is best 75 illustrated by 10, Fig. 5. The pivotal connections of the links are designated by 11.

Particularly referring to the logging industry, in which this device is especially useful, this rope grip is utilized in the following manner. In skidding logs through the woods by means of a donkey engine and blocks and tackle, it is necessary to establish what is termed in the industry "a high lead for donkies", i. e., blocks and tackle are 80 mounted on a high tree or pole to facilitate the movement of the ropes and the logging operations. In order to steady the tree or pole thus used, it is braced by guy ropes extending to other trees or suitable objects. In 85 fastening these guy ropes heretofore the practice has been to make a turn of the rope around a supporting tree or object and spike the rope thereto, to make additional turns of the rope, secured by more spikes, and then 90 to fasten the free end of the rope to the main portion of the rope by means of one or more U bolts. This method is wasteful of time, and the spikes, which are expensive, are in 95 most cases a total loss. In utilizing my in- 100 vention, the free end of the rope is inserted through a casing 1, and one or more turns of the rope made around a tree or other supporting object, the free end of the rope then being inserted through the other casing 105 of the device. A forward movement of one casing simultaneous with a backward movement of the other casing, causes the cam faces of the links to engage the shoes in the casings, and these in connection with the recessed faces of the shoes and the casings, 110 make the device effectually grip and retain

the sections of rope within it; in fact, the harder the pull on the rope, the tighter it is held. Fig. 1 illustrates the device as gripping the rope. To release the grip, tension is taken from the body of the rope, and a movement the reverse of that with which the device is applied releases the cam faces from the shoes, as illustrated in Fig. 3, when the rope can be easily withdrawn from the fastener. The device is effective in operation, can be applied and removed quickly, and will minimize the wear on the rope.

Fig. 6 illustrates in cross-section a modified form of this invention. In it the construction is the same as heretofore described, except that the shoes are dispensed with, and instead of the links having right angular cam faces, the links are provided with cam faces that are concave, as shown at 12, and striated, if desired, so as to better grip the rope. It is used in the same manner as the preferred form.

Changes in and modifications of the construction described may be made without departing from the spirit of my invention or sacrificing its advantages.

I claim:

1. In a rope grip, the combination of a pair of elongated rope casings adapted to afford an equal, and a substantial longitudi-

nal purchase on oppositely disposed sections of a rope, and substantial hand-hold portions in adjustment of said grip, the inner portions of the casings provided with recesses adapted to conform to the strands of a rope, connecting said casings, a plurality of links circular in outline at each end and eccentrically and pivotally mounted, said ends defining in operation cam faces within 40 the casings.

2. A device of the class described, comprising a pair of complementary members, the bodies of which are substantially U shaped in cross-section, their curved inner 45 portions provided with recesses adapted to conform to the strands of a rope, a plurality of links pivotally and eccentrically mounted, operating within and connecting said members, the ends of said links provided with 50 right angular cam faces, operatively associated with said cam faces and mounted within each member, a movable shoe provided with a flat surface on the portion adjacent the cam faces, the opposite side of the 55 shoe, adjacent the inner curved portion of said member, being curved and having, complementary to the recesses in said member, recesses adapted to conform to the strands of a rope.

JOHN G. ANDERSON.
